(57) **CLAIM**

The ornamental design for a pet toy, as shown and described.

DESCRIPTION

FIG. 1 is a perspective view of a pet toy showing my new design.

FIG. 2 is a front view of a pet toy showing my new design.

FIG. 3 is a rear view of a pet toy showing my new design.

FIG. 4 is a left side view of a pet toy showing my new design.

FIG. 5 is a right side view of a pet toy showing my new design.

FIG. 6 is a top view of a pet toy showing my new design; and,

FIG. 7 is a bottom view of a pet toy showing my new design. The broken lines depict environmental subject matter and form no part of the claimed design.

1 Claim, 6 Drawing Sheets
